UNITED STATES PATENT OFFICE

170,324

CLOCK CASING

Frederick Lux, Middlebury, and Helmut D. Beerbaum, Wolcott, Conn., assignors to The Lux Clock Manufacturing Company, Inc., Waterbury, Conn., a corporation of Connecticut

Application July 19, 1952, Serial No. 20,688

Term of patent 14 years

(Cl. D42—7)

To all whom it may concern:

Be it known that we, Frederick Lux and Helmut D. Beerbaum, citizens of the United States, residing in Middlebury and Wolcott, respectively, county of New Haven, and State of Connecticut, have invented a new, original, and ornamental Design for a Clock Casing, of which the following is a specification, reference being had to the accompanying drawing, forming a part thereof.

Fig. 1 is a front elevation of a clock casing, showing our new design.

Fig. 2 is a side view of the same.

Fig. 3 is a rear view of the same.

Fig. 4 is a bottom view of the same.

We claim:

The ornamental design for a clock casing, substantially as shown.

FREDERICK LUX.
HELMUT D. BEERBAUM.
